UNITED STATES PATENT OFFICE.

ARTHUR A. KRAEUTER, OF SOUTH ORANGE, NEW JERSEY.

DESIGN FOR A MEMBER OF A PAIR OF PLIERS, CUTTERS, AND SIMILAR ARTICLES.

46,681.

Specification for Design.

Patented Nov. 24, 1914.

Application filed July 15, 1914. Serial No. 851,185. Term of patent 14 years.

To all whom it may concern:

Be it known that I, ARTHUR A. KRAEUTER, a citizen of the United States, residing at No. 117 Vose avenue, South Orange, in the county of Essex and State of New Jersey, have invented a new, original, and ornamental Design for a Member of a Pair of Pliers, Cutters, and Similar Articles, of which the following is a specification, reference being had to the accompanying drawing, forming part thereof.

Figure 1 is a side view of a member of

a pair of pliers showing my new design, and Fig. 2 is an edge view taken at right angles to Fig. 1.

I claim:

The ornamental design for a member of a pair of pliers, cutters and similar articles, as shown.

ARTHUR A. KRAEUTER.
